N. W. SHELDON,

GASIFYING DEVICE,

APPLICATION FILED NOV. 8, 1920.

1,391,280.

Patented Sept. 20, 1921.

INVENTOR:

NOBLE W. SHELDON,

BY:

Ollie D. Rineger
his Atty.

UNITED STATES PATENT OFFICE.

NOBLE W. SHELDON, OF LOS ANGELES, CALIFORNIA.

GASIFYING DEVICE.

1,391,280.

Specification of Letters Patent. Patented Sept. 20, 1921.

Application filed November 8, 1920. Serial No. 422,664.

To all whom it may concern:

Be it known that I, NOBLE W. SHELDON, a citizen of the United States, residing at Los Angeles, in the county of Los Angeles and State of California, have invented a new and useful Gasifying Device, of which the following is a specification.

This invention relates to devices for transforming liquid fuel into gaseous fuel.

One of the objects of this invention is to provide a device which can be used as a burner as well as for carbureting purposes.

Another object is to provide a device which can be used for gasifying industrial liquors.

Another object is to provide means in such a device for gasifying a passing liquor to be used at an outside point in gaseous form.

Another object is to provide heating and gas discharging means in such a device so that a continuous stream of gas may be discharged while at an independent point a continuous heating and gasifying is accomplished.

Another object is to provide adjustable gas discharging means within the device.

Another object is to provide adjustable heat developing and gasifying means within the device.

Another object is to provide gas starting means for the device.

Other objects will appear from the following description and appended claims as well as from the accompanying drawing, in which—

Figure 1 is a midsectional view of the device.

Fig. 2 is a top plan view of the device.

The top of the device is preferably made of a suitable number of plates, in the drawing, the three plates 3, 4 and 5 form this top, but, of course, it will easily be understood that any other number of plates may be provided without departing from the principle of this invention.

Having three plates provided in the top, the uppermost plate 3 forms the cover plate, which is only provided with the central hole

6. The two other plates are provided, besides the central holes with holes 7, 8, 9, and 10; and, besides that, with grooves 11 and 12. The groove 11 is shown to be in the plate 4, having communication with the

holes 7 and 8. The groove 12 is shown to be

in the plate 5, having communication with the holes 9 and 10.

The several plates are preferably attached together in such a sealed condition that the grooves may form closed and independent conduits embodied in the top. Such attaching may of course be accomplished in many different ways, as by soldering, welding, bolting and packing, and other similar well-known processes.

Using the tube 13 for the feeding conduit, naturally brings the fuel through the conduits 14 and 15 into the grooves 11 and 12.

Any fuel entering the groove 11 through the hole 8 naturally passes through the groove 11 to leave the groove 11 through the hole 7. Any fuel entering the groove 12 through the hole 9 naturally passes through the groove 12 to leave the groove 12 through the hole 10.

Passing through the groove-conduits 11 and 12, the fuel is transformed into a gaseous form, in which state it enters the conduits 16 and 17. The conduits 16 and 17 unite at the point 18 into the conduit 19, which is preferably controlled by a valve 20.

In case the device is being used as a burner, a pan 21 is provided for igniting and preheating the device preparatory to starting the burner for use as such. A small amount of liquid fuel or similar material is disposed in this pan 21, hydrocarbons being especially adapted for this purpose, this is then ignited, and the flame from this then naturally tends to heat the top to such an extent as to gasify any fuel passed through the conduits 14 and 15 into the grooves 11 and 12 of the top. The gas resulting from this is passing through the conduits 16, 17 and 19 into the burner proper, as will be understood with the further detailed explanation hereafter.

Using the device as a mere gas-developing or gasifying device, it is naturally preferred, and almost necessary to provide an electrical contrivance to heat the top of the device for starting as well as for operating the device. Such a contrivance is indicated at 22 close below the top. It will easily be understood that such a contrivance can be arranged and proportioned so as to properly heat the top, as by a coil and other similar means.

Using the device as a burner, a secondary nozzle 22 is provided and disposed so that

the flame from this nozzle can spread and influence the top by heat to such an extent as required for developing gas and gasifying the fuel passing through the device in the manner described above. This secondary nozzle is naturally provided with a suitable number of orifices 23. By these orifices 23 a certain amount of gas escapes, and, igniting, spreads over the top to a suitable extent 10 to properly heat the top for gasifying the fuel passing through the conduits in the top.

The main nozzle 24 forms the termination of the conduits having a discharge orifice 25 so as to pass the gas upwardly through the 15 hole or orifice 6 in the top. This main nozzle is furthermore provided with threads, indicated at 26, allowing a connecting of a pipe or other similar means for transmitting the gas from the device to the point of consumption or use in case the device is only used as a device for developing gas and gasifying the fuel passing through the device. The threaded portion, indicated at 27 is provided for adjusting the main nozzle 24 closer 20 to or farther away from the top.

A coupling 28 is provided for adjustably engaging with the threaded portion, indicated at 29, of the secondary nozzle in a direction toward or away from the top.

30 A sleeve, embodying several sieves, is preferably inserted in the intake end of the device, the sleeve being indicated at 30 and three sieves being indicated at 31, 32 and 33. The sieves being preferably made of different grades, that is of different mesh, coarser to finer.

The main nozzle 24 is provided with an extension end 34 extending into the sleeve portion of the secondary burner 22a. The 40 extension end 34 of the main nozzle 24 is proportioned so as to leave a space 35 only large enough to allow a suitable amount of gas to pass inside of the sleeve or neck end of the secondary nozzle surrounding the extension end 34 to keep the flame of the secondary nozzle burning for the purpose of heating the top.

The threaded portion 27 of the main nozzle is on the other hand proportioned so as 50 to shut off the space or passage 35 when the lower end 36 of the threaded portion of the main nozzle is adjusted so as to seat this lower end 36 on that passage 35. In the drawing, the passage is illustrated as rather large, but it will easily be understood that this is done only for the sake of making it clear and distinct that there is such a passage, and it will easily be understood that such a passage and such a threaded portion 60 can be so proportioned as to allow such a shutting off of the passage by screwing and adjusting the main nozzle into the secondary nozzle. Using the device as a mere gas developing or gasifying device naturally 65 makes it necessary to eliminate the flame of

the secondary or at least makes it preferable to use such heating means that do not require such an extra flame. In such a case the main nozzle 24 is screwed into the secondary nozzle so as to shut off the passage 70 35. The electric contrivance, indicated at 22 is preferred in such a case. But, of course, a flame may just as well be burned as long as a connecting pipe is screwed over the main nozzle in such a manner as to completely shut off any leak in such a connection. 75

In the drawing, the grooves or conduits 11 are illustrated as coming in between the grooves or conduits 12 of the next plate, but 80 it will of course be understood that this is not necessary since the conduits do not in the least interfere one with the other, and it will also be understood that quite a few more circulation in each conduit may easily 85 be provided by circulating the conduits closer than illustrated in the drawing.

A top piece 37, provided with a suitable number of orifices 38, is disposed over the orifice 6 of the top when the device is used 90 as a burner.

Having thus described my invention, I claim:

1. In a gasifying device, a top consisting of a number of plates having circulating 95 grooves in one of their flat surfaces such as circulating grooves in one plate being covered by the next plate when the plates are so united into the top form.

2. In a gasifying device, a top consisting 100 of a number of plates having circulating conduits in their surfaces so that the conduits in the surface of one plate is covered by the adjoining plate when the several plates are united to form the top, intake 105 conduits having communication with the one end of the conduits in the top, and outlet conduits having communication with the other termination of the same conduits in the top.

3. In a gasifying device, a top consisting of a number of plates having circulating conduits in their surfaces so that the conduit in the surface of one plate is covered by the adjoining plate when the several 115 plates are united to form the top, intake conduits having communication with one termination of the conduits in the top, outlet conduits having communication with the other termination of the same conduits in 120 the top, in inlet conduit having means to be connected to the fuel supply, and a nozzle having communication with the outlet conduits.

4. In a gasifying device, a top consisting 125 of a number of plates having circulating conduits in their surfaces so that the conduit in the surface of one plate is covered by the adjoining plate when the several plates are united to form the top, an intake 130

conduit having a number of branches according to the number of conduits in the several plates in the top in communication with one termination of such conduits in the top, and an outlet conduit having a number of branches according to the number of conduits in the top in communication with the other termination of the same conduits in the top, the conduits being so arranged that fuel can be directed from the intake conduit 10 equally through the several branches and through the several conduits in the top to be discharged through the several branches into the outlet conduit.

15 5. In a gasifying device, a top having circulating conduits embodied in the material having also inlet and outlet conduits in communication with the conduits in the top and having a discharge passage through the 20 top, preheating means disposed below the top, and a gas nozzle having communication with the outlet conduit of the top disposed under the top and having its discharging orifice disposed in the direction through the 25 discharge passage in the top.

6. In a gasifying device, a top having circulating conduits embodied in the material having also inlet and outlet conduits in communication with the conduits in the top and 30 having a discharge passage through the top, a preheating nozzle disposed below the top in communication with the outlet conduit of

the top having means for adjusting the nozzle in the direction toward and in relation to the passage in the top, and a main discharge nozzle disposed below the top in communication with the outlet conduit of the top having adjusting means for adjusting the nozzle in relation to the passage in the top.

7. In a gasifying device, a top having circulating conduits embodied in the material having also inlet and outlet conduits in communication with the conduits in the top and having a discharge passage through the 40 top, a preheating nozzle disposed below the top in communication with the outlet conduit of the top having means for adjusting the nozzle in the direction toward and relation to the passage in the top, and a 45 main discharge nozzle disposed below the top in communication with the outlet conduit of the top having adjusting means for adjusting the main nozzle in relation to the passage in the top adapted to shut off the 50 preheating nozzle from the outlet communication with the top.

In testimony that I claim the foregoing as my invention I have signed my name in the presence of two subscribing witnesses.

60 NOBLE W. SHELDON.
